PROTECTOR-REMOVING DEVICE

Raymond G. Taylor, Jr., Santa Monica, Calif., assignor, by mesne assignments, to Borg-Warner Corporation, Chicago, Ill., a corporation of Illinois

Continuation of application Ser. No. 185,468, Sept. 18, 1950. This application Mar. 29, 1954, Ser. No. 419,266

15 Claims. (Cl. 29—236)

This invention relates generally to well drilling equipment and more particularly to a device useful in apparatus for removing protectors from drill pipe.

In the drilling of wells by the rotary method, one of the ever-present problems is that of wear on the drill pipe and on the inner wall of the casing installed in the well, such wear being occasioned by likely contact between said drill pipe and casing. Hence, it is common practice in the rotary drilling art to apply to the string of drill pipe numerous resilient protectors. Such protectors are usually composed of rubber or rubber-like material and are spaced at proper intervals upon the string of drill pipe to prevent contact of the drill pipe and particularly of the tool joints thereof with the casing.

These protectors ordinarily comprise cylinders which when installed thereon encompass the pipe. In order that they may tightly grip the pipe and thereby prevent slippage, the protectors are molded with their internal diameters smaller than the external diameter of the pipe and are thus difficult to remove from the drill pipe over the tool joint without damage when such removal is desirable. After a protector-equipped string of drill pipe has been used in drilling a well the protectors are usually but slightly worn and therefore re-usable in the drilling of another well. If such pipe string is to be used shortly thereafter to drill a second well, the protectors mounted thereon may safely remain on the pipe. If, however, such pipe is not to be used for some time it is preferable that the protectors be removed therefrom and placed in protective storage. Such storage will avoid damage to the protectors resulting from exposure to the elements while under tension upon the pipe, the pipe usually being stored in open unprotected racks when not in use.

Heretofore, several devices have been suggested for removing protectors from drill pipe. Generally, such devices comprise a base member adapted to be secured to the floor of a derrick and having upwardly extending arms. The upper end of the arms includes hooks or other means for engaging a pipe-mounted protector. For the removal operation the pipe is suspended in the derrick adjacent the device and the protector-engaging means are connected to the upper end of a protector to be removed from the pipe. The pipe is then elevated whereby the protector is pulled off over the bottom end thereof. Such devices have proven fairly satisfactory, but inasmuch as they require the use of the derrick equipment and the drilling crew, the usual drilling operations must necessarily be delayed during the protector-removing process and thus considerable added expense occasioned. Furthermore, a considerable number of protectors are ordinarily torn in removal with this type of device, since the pipe is not always elevated at that angle which permits the protector-engaging means to exert a uniformly distributed removal force upon the upper end of the protector. Additionally, the use of these prior devices involves an appreciable risk to certain members of the drilling crew who are required to be stationed below the suspended length of drill pipe during the protector-removing operation.

Thus, any failure of the hoisting mechanism or miscalculation or carelessness of the operator thereof can easily result in serious injury to the crew members.

In a copending application for United States Letters Patent, entitled "Apparatus for Removing Protectors from Pipe," Serial No. 185,466, filed Sept. 18, 1950, by De Mont G. Miller and Rodney R. Wood, there is, however, shown a power apparatus for removing protectors from pipe, which apparatus may be operated independent of the derrick and away therefrom, and which apparatus thus avoids the above difficulties. Generally such apparatus consists of a pipe-engaging means abuttable against the extremity of the drill pipe and tension members connected to the pipe-engaging means, which tension members are adaptable for connection to protector-engageable means. The pipe-engaging means consists of a relatively movable plunger-cylinder assembly, which enables an element to which the tension members are connected to be moved relatively away from the pipe end to cause the protector-engageable means to push the protector on over the end of the pipe. The protector-engageable means, as disclosed in such application, consists of hook-shaped dogs having hooks or lips which engage the protector by grasping the same between the pipe surface and the inner diameter of the protector. Such type of protector-engageable means, and indeed others of similar structure, have proven generally satisfactory for protector-removing operations but certain disadvantages occur in their use. The certain disadvantages occur in their use particularly where are involved unusually stubborn protectors, or where are involved drill pipe tool joints having such conformity as to present shoulders extending radially outwardly from the surface of the drill pipe in such degree as to render the passage of the protector thereover unusually difficult. Here the presence of hooks and the like fails to present an optimum uniform distribution of abutting force about the periphery of the end of the protector and increases the tendency to split the protector at one of the hooks. Further, they increase the tendency of one or more of the hooks to hang up on the pipe and generally render the protector-removing operation more difficult.

Consequently, it is the principal object of the present invention to provide a protector-engageable device which may be used with apparatus for removing protectors from pipe and which will uniformly distribute the protector-abutting forces at the end of the protector.

It is a further object of the present invention to provide such a protector engageable device which will reduce the possibility of tearing or otherwise damaging a protector during the removal operation.

Yet another object of the invention is to provide such a device which may be simply and quickly applied to the protector.

A further object of the invention is to provide protector-engageable apparatus which will not tend to hang up on the pipe during the removal operation.

Another object of the invention is to provide such a device capable of applying a uniformly distributed force to the protector, but at the same time capable of being positively held in close pipe-encompassing position whereby to engage the protector with a minimum danger of pinching portions of said protector against the pipe or of riding over the protector and thus failing to remove the same.

Yet another of the objects of this invention is to provide such a protector-engageable device capable of outward movement with respect to the pipe whereby to accommodate itself to a tool joint, or the like, of greater diameter than that of the pipe.

Other objects and advantages of the present invention will be apparent from the following detailed description,

taken in conjunction with the accompanying drawings wherein:

Figure 1 is a top view of a protector-engageable device embodying the present invention, operatively connected to protector-removing apparatus and in position to remove a pipe-mounted protector.

Figure 2 is a side elevational view of the device of Figure 1.

Figure 3 is a front elevational view of the device of Figures 1 and 2 taken on the line 3—3 of Figure 2 from which view the protector itself has been omitted.

Figure 4 is a cross-sectional view of the device taken on the line 4—4 of Figure 2.

Figure 5 is a partial longitudinal sectional view taken on the line 5—5 of Figure 3.

Figure 6 is another partial longitudinal sectional view taken on the line 6—6 of Figure 3.

Figure 7 is a fragmentary front elevational view of the protector-engageable device shown in the preceding figures as modified for use in removing protectors from smaller size pipe.

Figure 8 is a partial longitudinal section of the device of Figure 7 taken on the line 8—8 of Figure 7.

Figure 9 is a partial longitudinal section of the device of Figure 7 taken on the line 9—9 of Figure 7.

With reference to the drawings, it will be seen that the invention in its general aspect comprises a pair of support arms 20 and 22, pivotally joined at one of their ends and integrally carrying a pair of abutment members 24 and 26 adapted to be clamped about the pipe 28 adjacent the protector 30 to be removed and to abut the end of said protector. The arms 20 and 22 are capable of connection to a protector-removing device generally designated 32, which device serves to draw the protector-engageable device of the instant invention along the pipe 28, so that it may remove the protector 30 over extremity 34 of the pipe 28. The support arms 20 and 22 and hence the abutment members 24 and 26 may be latched positively about the pipe 28 in close conformity thereto by means of the releasable limit means or latch 36, but due to the pivotal interconnection between the said arms, upon release of said latch 36, said arms, and consequently the abutment members, are capable of transverse movement outwardly of the pipe to permit the device to pass over the pipe tool joint 38. The aforesaid transverse movement is resiliently constrained by the spring assembly 40.

The particular protector-removing device 32 shown operating in conjunction with the instant invention is set forth in detail in the aforementioned application of Miller and Wood but may be described here briefly as follows. A plunger 42, extending from a cylinder 44, is either of such conformation or mounts an adapter 46 as to permit abutment of the pipe extremity 34. The cylinder 44 through fluid pressure introduced through the fittings 48 and 50 may be caused to slide outwardly from the said pipe on the plunger 42 and carries a yoke 52, said yoke 52 having an arcuate passageway 54 through which passes a chain 56 connected by the slotted hooks 58 and 60 to the device of the instant invention. Thus, when fluid pressure is admitted to the cylinder 44 to cause outward movement thereof with respect to the plunger 42 and the pipe 28, the chain 56 draws the support arms 20 and 22 and the abutment members 24 and 26 along the pipe 28. Such abutment members engage the protector 30, forcing said protector along the pipe 28 over the tool joint 38 and beyond the pipe extremity 34. If desired, the releasable latch 36 may be utilized to prevent any outward transverse movement of the arms 20 and 22, and hence the abutment members 24 and 26, until the tool joint 38 is reached, whereupon release of said latch will permit the resiliently restrained outward movement of said arms and abutment members to the diameter of the tool joint. Thus, in the protector-removing operation surface contact against the

protector whereby to provide uniform force distribution is assured, the likelihood of tearing the protector minimized, positive latching of the support arms and abutment members against outward transverse movement made available whereby to minimize possible pinching of the protector against the pipe, and resiliently constrained outward movement of the support arms and abutment members permitted to accommodate passage of the device over the tool joint.

Referring more particularly to the details of construction of the invention, the support arms 20 and 22 are preferably of tubular construction and include slots 62 at one of their extremities wherein the slotted hooks 58 and 60 may be rigidly secured, as by welding. The ends 10 of the arms 20 and 22 may be beveled as at 64 adjacent the slotted hooks so as to facilitate the interconnecting and the disconnecting of the chain 56 with respect to said hooks.

The opposite ends of the support arms 20 and 22 are rigidly secured, as by welding, to a pair of pivot plates 66 and 68, respectively. Pivot plate 68 includes a pair of lugs 70, and pivot plate 66 includes a cooperating lug 72, which lugs are provided with aligned bores adapted to receive a pivot pin 74. This pivot pin is secured by a cotter pin 76 extending through the lug 72. Adjacent the lower lug 70 and also carried by the pin 74 is a guide tongue 78 which, as will be seen hereinafter, is to prevent any possible hang up of the pivot assembly on the tool joint 38 during the protector-removing operation. It will be noted that when the device is in position to remove a protector from a pipe, the support arms 20 and 22 are adapted to straddle the pipe 28 with the pivot assembly disposed atop the pipe, and the slotted hooks 58 and 60 spaced substantially equidistant from opposite sides of the pipe. The abutment members 24 and 26 are as shown rigidly secured, as by welding, to one of the support arms 20 and 22, respectively, at such angle that they will be disposed transversely to the pipe 28 when the protector-engageable device is in position to remove a protector. A reinforcing gusset 80 may be provided for each abutment member to strengthen the attachment thereof to its respective support arm. Each abutment member is seen to comprise broadly a generally triangular base plate 82 formed with a pipe-receiving recess 84 and an arm-receiving recess 86. The pipe-receiving recess 84 should be of a radius whereby its edges will be closely spaced to, but not in contact with, the periphery of the pipe 28, as shown in Figure 3. A pusher pad 88 of rubber or rubber-like material is mounted on each base plate adjacent the pipe-receiving recess and in overlapping relation thereto, preferably with its inner edge lightly contacting the periphery of the pipe. Each pusher pad 88 is preferably secured to the face of its respective base plate 82 by means of a mounting plate 90 having integral attachment pins 92 adapted to be extended through bores 94 formed in the pusher pads. The pins 92 are retained in the bores 96 in the base plate 82 by lock washers 98 and nuts 100. These pins may include a portion of enlarged diameter 102, whereby there is formed an abutment surface 104 adapted to shoulder upon the face of each base plate to prevent excessive deformation of the pusher pads 88 through overly tight threading of the nuts 100. It should be understood that it is not essential that the pusher pads 88 be formed of rubber or rubber-like material. Such pads may instead be formed of other material having deformable characteristics to avoid damaging protectors during their removal. It will be noted that each base plate 82 is shown formed with a flange 106 to provide transverse support for the pusher pads 88.

The releasable latch 36 comprises a latch bolt 108 rigidly secured, as by welding, at one of its ends to a support bracket 110, and threaded at its other end so as to receive an adjusting nut 112 and a lock nut 114. The support bracket 110 is shown disposed between a spacer 116 secured to the rear surface of the base plate 82 of

abutment member 26 and a mounting lug 118 spaced from the spacer 116 by a bridging element 120. The lug 118 may be rigidly secured to the support arm 22, as by welding. A pivot pin 122, supported within aligned bores formed in the base plate 82, the spacer 116 and mounting lug 118, respectively, is shown extending through the bore 124 in the support bracket 110 so as to pivotally support the latch bolt 108, the said pivot pin 122 being secured by a cotter pin in the usual manner. A cradle 126, having a trough 128, is rigidly secured, as by welding, to the support arm 20 and to the other base plate 82 of the abutment member 24. Such cradle 126 is adapted to receive the threaded end of the latch bolt 108, so as to restrict the maximum transverse separation between the abutment members 24 and 26 by the engagement of the side surface 130 of the said cradle with the adjusting nut 112. Such separation may be varied by manipulation of the two nuts 112 and 114 with respect to the threaded end of the latch bolt 108.

The spring assembly 40, which is adapted for operation during release of the latch 36, comprises a horizontally disposed bolt 132 slidably carried in bores 134 formed in lugs 136 rigidly secured to the upper portion of the base plate 82 of the abutment members 24 and 26. A sleeve 138, disposed on the bolt between the two lugs 136, serves to maintain a minimum transverse clearance between the abutment members. Two springs 140 and 142 are positioned each between one of the lugs 136 and washers 144 and 146, respectively, which washers are in turn, respectively, backed by an adjusting nut 148 held by a lock nut 150 secured to the threaded end of the bolt and by the bolt head 152. To adjust the spring pressure, the bolt head 152 may be held against rotation while the two nuts 148 and 150 are screwed or unscrewed on the bolt. The bores 134 are of sufficient diameter to permit the bolt 132 to slide freely therein, whereby each spring 140 and 142 will be tightened or loosened to the same degree.

In the operation of the above-described apparatus, it is first necessary to apply the protector-engageable device to the pipe. For this purpose, the latch bolt 108 is raised from the cradle trough 128 permitting resiliently constrained transverse separation of the abutment members 24 and 26. The operator may force these members apart as by sharply urging the device downwardly toward the pipe whereby the inclined lower surfaces 154 of the base plates 82 will strike the sides of the pipe and thus cam the members apart sufficiently to allow the device to assume the operating position shown in the drawings. The latch bolt 108 may then be disposed in locking position with its threaded end in the cradle trough 128, the adjusting nut 112 of the latch being so adjusted that the inner edges of the pusher pads 88 substantially correspond to the periphery of the pipe. With this arrangement, any likelihood that the pusher pads may be pulled over the protector during the initial loosening of the protector is substantially eliminated. It will, of course, be appreciated that in the case of an easily loosened protector, the latching operation may be dispensed with and the spring assembly 40 depended upon to prevent over-riding of the protector. It is recommended that a lubricant, such as soap solution, be applied to that portion of the pipe and tool joint over which the protector will be moved.

Connection may be then made between the aforesaid device and the protector-removing device 32 by connecting the chain 56 to the slotted hooks 58 and 60. It is recommended in this step that one of the end links of the chain 56 be connected to a hook and the chain pulled through the arcuate passageway 54 and hooked at an intermediate link on the other side of the device to avoid slack in the said chain. Fluid pressure may now be admitted to the cylinder 44 to cause it to move axially away from the pipe extremity 34. Such axial movement will be transferred to the yoke 52, the chain 56 and, in turn, to the protector-engageable device. This device,

through engagement of the pusher pads 88 with the end of the protector, will urge the protector toward the end of the pipe. It will be particularly noted that inasmuch as an appreciable area of each pusher pad is in contact with the end of the protector during this operation, the unit bearing pressure acting against the protector is comparatively small whereby there is less danger of either pad tearing the protector.

- In the event that the releasable latch has been used 10 in latched position as the protector rides onto the tool joint 38 and as the abutment members 24 and 26 approach the tool joint, it will be necessary to release said latch to permit the abutment members to separate sufficiently to allow the pusher pads 88 to follow the contour 15 of the tool joint. The springs 140 and 142 should be so adjusted as to exert sufficient closing force upon the abutment members to make certain that the pusher pads will remain closely spaced to the periphery of the tool joint as the protector is urged along and over the joint.
- 20 If each protector to be removed is positioned adjacent the tool joint of the pipe at approximately the same distance from the end of the pipe as shown in Figure 1, it will not be necessary to alter the distance between the protector-engageable device and the yoke 52. Frequently, however, a protector will have slipped along the pipe to a position further removed from its end. Accordingly, the chain 56 should be of sufficient length to reach these axially displaced protectors. Ordinarily, a single stroke of the protector-removing device 32 will not be 25 sufficient to completely remove the protector, and the chain 56 will have to be disconnected and reconnected to take up slack therein. It has been found most convenient when removing such protectors to leave one end of the chain connected to one of the slotted hooks 60 and to 30 detach the chain from the other slotted hook 58 to take up slack, after which the chain may be reconnected for 35 another stroke of the said protector-removing device. This procedure may be repeated as many times as required in order to remove the protector from the pipe.
- 40 It should be particularly pointed out that occasionally a protector will be encountered which will require considerable initial removal force in order to loosen its grip upon the pipe, although after such a protector is loosened a much lesser force would be sufficient to move it off the pipe. The provision of the releasable latch 36 to positively lock the abutment members 24 and 26 against transverse separation eliminates the possibility of the pusher pads 88 overriding the end of the protector during the application of a necessarily strong initial removing force. However, as pointed out hereinbefore, the 45 latch may be dispensed with entirely and the constraining force of the spring assembly 40 relied upon to prevent undue transverse separation of the abutment members during the protector-removing operation. This, of course, limits the effectiveness of the device to the more 50 normally adhering protector, although if the springs 140 and 142 be tightened sufficiently, even tight protectors may be removed in the absence of the latch. On the other hand, such expedient would make application of the device exceedingly difficult due to the necessity of 55 camming open the abutment members 24 and 26 when installing the apparatus. It will also be appreciated that for the removal of protectors and the like from pipe having no section of increased diameter, such as the tool joint 38, the spring assembly 40 may be dispensed with and the releasable latch 36 relied upon solely.
- 60 Referring now to Figures 7, 8 and 9, there is shown a manner whereby the aforesaid protector-engageable device may be adapted for use with smaller size pipe 156. In this modification an adapter element 158 is interposed between each pusher pad 88 and base plate 82. Each adapter element 158 is formed with a pipe-receiving recess 160 having a radius such that its edge will be closely spaced to, but not contact with, the periphery 65 of the pipe 156. The adapter elements are formed with

bore 162 to receive attachment pins 92 of the mounting plate 90 and serve to back up the pusher pads 88 which, however, will preferably slightly overlap the adapters to lightly engage the periphery of the pipe.

It will be apparent to those skilled in the art that various other modifications and changes may be made without departing from the essence of the invention, and it is intended to cover herein all such modifications and changes as are within the true scope and spirit of the appended claims.

This application is a continuation of my application Serial No. 185,468, filed September 18, 1950, now abandoned.

I claim:

1. In a means for removing protectors from pipes having enlarged sections, a protector engaging apparatus comprising; a plurality of abutment members having surfaces for engaging a protector and having arcuate edges defining an aperture for receiving and encompassing a pipe, means to one side of said aperture connecting said abutment members together for movement relative to one another, said means including a spring assembly attached to said abutment members for forcing said members together, said abutment members defining a radial access opening to said aperture diametrically opposite to said spring assembly, said access opening always being unobstructed, said abutment members being transversely separable against the urging of said spring assembly to allow a pipe to pass through said access opening and to allow said abutment members to ride transversely out and over any enlarged sections in a pipe encompassed thereby.

2. A device as set out in claim 1 wherein said spring assembly includes a bore defining member mounted on each abutment member, a bar slidably disposed in said bores and having spring stop means at opposite ends thereof, and springs mounted on opposite ends of said bar and compressed between said bore defining members and said spring stop means.

3. A device as set out in claim 2 wherein at least one of said spring stop means is adjustable to vary the effective length of said bar to vary the constraint exercised by said springs.

4. A device as set out in claim 1 including a releasable limit means interconnecting said abutment members independently of said spring assembly to provide a stop against said transverse separation.

5. A device as set out in claim 4 wherein said limit means is located adjacent said spring assembly on the diametrically opposite side of said aperture from said access opening.

6. A device as set out in claim 1 wherein each of said abutment members comprises a planar portion having edges which constitute said aperture defining edges, said aperture being of such a diameter that said edges terminate in close proximity to a pipe encompassed by said abutment members, and rubberlike deformable pads carried by said planar portions and having bearing surfaces lying in a plane transverse to a pipe in said aperture, said pads overlapping said edges of said planar portions and having edge surfaces engageable with a pipe in said aperture.

7. In a means for removing protectors from pipes having enlarged sections, a protector engaging apparatus comprising; a plurality of abutment members having surfaces for engaging a protector and having arcuate edges defining an aperture for receiving and encompassing a pipe, means connecting said abutment members together for movement relative to one another, said means including a plurality of connecting members each secured respectively to one of said abutment members, means movably interconnecting said connecting members to permit relative movement of said abutment members toward and away from each other, a spring assembly attached to said abutment members to one side of said aperture for forc-

ing said members together, said abutment members defining a radial access opening to said aperture diametrically opposite to said spring assembly, said access opening always being unobstructed, said abutment members being transversely separable against the urging of said spring assembly to allow a pipe to pass through said access opening and to allow said abutment members to ride transversely out and over any enlarged sections in a pipe encompassed thereby.

10. 8. A device as set out in claim 7 including a releasable limit means interconnecting said abutment members independently of said spring assembly to provide a stop against said transverse separation, said limit means being located on the diametrically opposite side of the said aperture from said access opening.

9. In a means for removing protectors from pipes having enlarged sections, a protector engaging apparatus comprising; a pair of abutment members having surfaces for engaging a protector and having arcuate edges defining an aperture for receiving and for encompassing a pipe, a pair of support arms, pivot means joining said support arms adjacent one pair of ends thereof, said support arms having their free ends attached to said abutment members on opposite sides of said aperture to

20. permit relative movement of said abutment members towards and away from one another, means adjacent said pivot means for causing the latter to slidably ride over a pipe which passes through said aperture, a spring assembly attached to said abutment members and being situated to one side of said aperture to normally urge said members together, said abutment members defining a radial access opening to said aperture diametrically opposite to said spring assembly, said access opening always being unobstructed, said abutment members being transversely separable against the urging of said spring assembly to allow a pipe to pass through said access opening and to allow said abutment members to ride transversely out and over any enlarged sections in a pipe encompassed thereby.

30. 10. A device as set out in claim 9 wherein said spring assembly includes a bore defining member mounted on each abutment member, a bar slidably disposed in said bores and having spring stop means at opposite ends thereof, and springs mounted on opposite ends of said bar and compressed between said bore defining members and said spring stop means.

35. 11. A device as set out in claim 9 including releasable limit means interconnecting said abutment members independently of said spring assembly to provide a stop against said transverse separation.

40. 12. A device as set out in claim 11 wherein said limit means is located adjacent said spring assembly on the diametrically opposite side of said aperture from said access opening.

45. 13. In a means for removing protectors from pipes having enlarged sections, a protector engaging apparatus comprising; a pair of abutment members having surfaces for engaging a protector and having arcuate edges defining an aperture for receiving and for encompassing a pipe, bore defining members mounted on said abutment members and defining bores in axial alignment and to one side of said aperture, a bar slidably disposed in said bores, stop means on opposite ends of said bar, springs mounted on said bar at opposite ends thereof between said bore defining members and said stop means to urge said abutment members together, said abutment members defining an unobstructed radial access opening to said aperture diametrically opposite to said bar; and releasable limit means interconnecting said abutment members on the same side of said aperture as said bar, said limit means comprising a bridging member having one end pivotally affixed to one abutment member and having its free end slidably and removably engaged with a catch means affixed to said other abutment member to

permit said abutment members to move toward each other but to limit their movement away from one another.

14. A device as set out in claim 13 wherein said separating movement of said abutment members is limited by an adjustable stop on said free end of said bridging member. 5

15. Apparatus for engaging a protector for removal of said protector from a pipe comprising: a pair of pivotally joined transversely separable support arms adapted to be slidably mounted on said pipe with each arm disposed at one side of said pipe, said support arms being connectible to a means for inducing axial movement thereof with respect to said pipe; abutment members carried by said support arms and movable therewith transversely of said pipe during removal of said protector therefrom to override protuberances on said pipe, said abutment members being adapted to assume a substantially encompassing relation about said pipe and having surfaces transverse to said pipe and engageable with said protector; a releasable latch adapted to interconnect said 10 15 20

support arms to provide a positive stop against said transverse separation; and a spring assembly connecting said abutment members to resiliently constrain said transverse separation.
